UNITED STATES PATENT OFFICE.

JACOB JENKINS, OF LYNN, MASSACHUSETTS, ASSIGNOR TO G. W. KEENE,
M. W. SHEPARD, AND J. C. STIMPSON.

IMPROVEMENT IN MACHINES FOR PREPARING HEELS FOR BOOTS AND SHOES.

Specification forming part of Letters Patent No. 36,586, dated September 30, 1862.

To all whom it may concern:

Be it known that I, JACOB JENKINS, of Lynn, in the county of Essex and Commonwealth of Massachusetts, have invented a new and useful Machine for Attaching and Finishing Shoe-Heels; and I do hereby declare that the following is a full, clear, and exact description of the construction and operation of the same, reference being had to the accompanying drawings, forming a part of this specification, in which—

Figure 1 is a front elevation with the rotary cutter 14, Fig. 6, removed. The other figures are views of the various parts detached and not so fully represented in Fig. 1.

Like parts are indicated by the same letters and figures in all the drawings.

To enable others skilled in the art to make and use my invention, I will now describe its construction and operation.

A A', Fig. 1, is a frame or table of iron, cast in one piece, a top view of the same being shown in Figs. 2 and 3.

B is a shaft turning in suitable bearings in the sides of the frame, and provided with a crank, B', and fly-wheel B'', as shown in Fig. 1.

C is a crank fast on the end of shaft B, and provided with a slot, (represented by the dotted lines in the side view, Fig. 10,) through which passes the crank-pin C'.

c is a screw passing through crank C and a hole in shaft B and into the crank-pin C', as shown by the dotted lines in Fig. 1, the object of said screw being to move crank-pin C' nearer to or farther from the shaft B, for the purpose hereinafter described.

D is a cast-iron arm, shaped as shown in Figs. 1 and 10, through the lower end of which passes the crank-pin C'.

F is a spindle turning in suitable bearings in the uprights F' F'', which are cast on the table A'.

E', Fig. 10, is a chain belt, one extremity of which is attached to spindle F, and the other (passing through the top of D and terminating with a screw-bolt link) is confined and kept sufficiently taut by means of nut D'. E is a similar chain belt, one end of which (see Figs. 1 and 10) is fast to the spindle F, and the other, passing through shaft D, Fig. 1, is confined and tightened by means of nut D''. Thus it is obvious that by rotating shaft B arm D will be carried up and down by crank-pin C', and the

chains E and E' will rock the spindle F, and through a greater or less arc of a circle according to the distance of crank-pin C' from B; and if said chains are kept tight, (as they may always be by means of nuts D' and D''), there will be no "backlash," in this respect being preferable to a rack and pinion.

G' is a block of steel, the end of which (see Fig. 7) is shaped like the bottom of a shoe-heel and partly surrounded by a band of steel, G, the two ends of which are united by means of a screw-bolt, 15.

16 is a groove formed by band G and a rabbit in block G', as shown in Fig. 7. A line passing round the center of this groove is the exact shape and about the size of the top edge of the heel to be made.

Through the center of G' is a hole (see Fig. 7) large enough to receive the spindle F, h being a nut to hold said block in place, as shown in Fig. 1. There should be as many of these blocks as there are different styles of heels to be made, one block answering for all sizes of the same pattern. To the extremity of spindle F is attached the heel-bed T, Fig. 1, the end of which is of the size and shape of a last-heel bottom. The end of T is roughened or provided with little points to keep the leather or shoe-heel S from slipping.

F'' F''' are uprights attached to the table A', through which passes the screw-shaft Q, the latter being prevented from turning by a longitudinal slot and a pin, in the usual manner. Through the center of wheel 17 is a female screw, so that by turning said wheel, shaft Q can be driven toward heel-bed T or from it, at pleasure.

R is a plate of hardened steel, a little smaller than the bottom of a shoe-heel, through the center of which, as shown in Fig. 8, is a hole, r, to admit a pin projecting the thickness of a shoe-heel from the center of the end of shaft Q.

H (a top view of which is shown in Fig. 2) is an adjustable slide extending across the table A', two edges of said table being beveled under, so as to form a dovetail tenon with the beveled mortises in the flanges on the under side of the two extremities of said slide. This slide is kept to its bearings on the table by means of screws s s passing through flange W' and against the beveled adjustable block or slide 22, Fig. 2.

U, Figs 1, 2, and 3, is a start cast on the under side of the table.

U' is a screw-bolt turning in U and screwing into start 3, Fig. 1, on the under side of slide H, by means of which screw-bolt it is obvious that H can be moved to the right or left. The object of this lateral movement of H is to adjust pivot Z in slide J, Fig. 4, directly under the face of the heel-bed T.

I (a top view of which is represented in Fig. 3) is another slide fitting over H and sliding on and guided by suitable ways on the extremities of H, as represented in Figs. 1 and 2, one extremity of H being beveled, as shown in Fig. 1, to fit a corresponding bevel in the flange on the under side of I.

18 and 19, Fig. 1, are screws for tightening block t and keeping I to its bearings. The farther end of I is held in place upon H by means of strip W, which is screwed onto strip W', Fig. 2.

X is a spring attached by screw 2 to a start on the under side of I, as represented by the dotted lines in Fig. 3. The opposite side of this spring rests against a start on the under side of W', as represented by the dotted lines in Fig. 3. The action of this spring is to force slide I and its appendages in the direction of the arrow, Fig. 3.

H' (the shape and position of which are shown in Figs. 1 and 3) is an upright arm of steel attached to the top of slide I, the upper end of said arm being bent, as seen in Fig. 1, so as to enter and slide in groove 16, Fig. 7. Thus as the groove 16 vibrates on its axis F it is obvious that slide I, with its appendages, will be moved backward and forward on slide H and carry the cutting and polishing tools P and 14, Fig. 6, so as to make the shoe-heel edge conform to the shape of groove 16.

I' is a start on the top of I and serving as a rest for the bottom of slide L. (See Fig. 1.)

I'' is a block of steel made to slide in a slot in slide I, as represented in Fig. 3.

i is a screw-bolt, the head of which turns in the front end of slide I, the end screwing into block I'', by means of which said block can be moved backward and forward in the slot in I.

Z' is a hole provided with a female screw in block I'' to receive the screw-pivot Z, Fig. 4, of slide J.

The use of screw-bolt i is to move slide J and its appendages to and from shaft F, so as to vary the size of the heel to be made without altering the angle of the cutter and polisher.

J (a top view of which is given in Fig. 4) is a slide resting on the top of slide I and made to partake of the motion of the latter by means of the pivot Z, which screws into the block I'', Fig. 3.

J' is a continuation of J, and provided with an upright arm, V, Figs. 1 and 4, the upper end of which arm bears against cam V', (between g and G, Fig. 1,) the arm being pressed against said cam by the action of spring 1, Fig. 3, and pin 8, Fig. 4, projecting below slide

J and bearing on said spring; and as the cam V' does not conform exactly to the shape of groove 16, but varies from it, as represented by the dotted lines in Fig. 7, at the end of the heel, the cutter and polisher (having a double motion) will be thrown out thereby, so as to make the end of the shoe-heel less beveling than the other parts, thus forming a more desirable and better-looking heel than could be produced by the machine without the use of said cam V'.

4 is a stationary beveled cleat attached to the top of J, and 5 is another beveled cleat, but made adjustable by means of the screws 7 7, passing through a start, 6, as shown in Fig. 4.

K is another slide, the shape of which is shown in the top view, Fig. 5. The ends of this slide are beveled so as to fit in between the cleats 4 and 5 on the top of J. On the under side of K is a start, 11, (represented by the dotted lines in Fig. 5,) into which screws the bolt j, whose head turns in a continuation of J, as shown in Fig. 4. The object of j is to move slide K and its appendages in a line parallel with the heel-edge, so as to carry the cutter and polisher to and from the shoe.

9, Fig. 5, is a beveled steel block sliding in the slot 10 in K, by means of which and pin 9', Fig. 6, which screws into it, slide L is confined to the top of K and also allowed to move.

k is a screw-bolt turning in K, as shown in Fig. 5, and screwing into a start on the under side of slide L, by means of which the latter, with its appendages, can be moved so as to carry the cutter and polisher to and from the shoe-heel at pleasure while the machine is in operation, the head of k being provided with a suitable key or crank, to be turned by hand.

L is a slide resting on the top of K and I', as shown in Fig. 1, and shaped as represented by the top view in Fig. 6. The under side of L has a flange on each side, so as to clasp slide K and be guided thereby when moved by screw-bolt k.

M, Figs. 1 and 6, is an arm attached to L by means of pivot m, on which it can be turned, and held in place by the overhanging plate L' and the screws which confine the latter to slide L.

N is an arm attached to the top of M by means of a screw, n. To one end of N is attached the tool rest or holder O, constructed like the rests in engine-lathes.

P' is the polishing-tool, of hardened steel, shaped as shown in Fig. 6, and held in place by the set-screw p.

P, Fig. 9, is a perspective view of a diamond-shaped cutter, which may be used in place of the polisher P', in Fig. 6, to pare the heel. I prefer, however, for most work, to make use of the rotary cutter 14 for paring and the polisher P' for polishing. The rotary cutter 14 is simply a plate of steel with its outer edge or edges beveled and sharp, and is confined to shaft 12 by a screw, as shown in Fig. 6. Shaft 12 turns in the uprights of plate 20, which is

attached to L by pivot 21. Plate 20 can be confined in the same manner as plate M by means of L'.

13 is a drum to be driven by a belt connected with a larger drum, which may be actuated by hand or other power.

It is also obvious that a rotary polisher may be substituted for the cutter 14, if desirable; but I prefer to pare the heel by means of the rotary cutter 14 and polish it with the polisher P'; or, again, there is still another way in which I propose to make use alternately of a diamond cutter, P, and polisher P'—that is, by combining and arranging them in the same stock or handle, as shown in the top view, Fig. 11, and perspective, Fig. 12. The stock 24, Fig. 11, rests upon arm N, to which it is attached by a screw-pivot, 25. The cutter is a flat piece of steel, the two edges of which are beveled so as to fit into a corresponding mortise in the stock, as shown in Fig. 12, and is confined by means of a bolt and thumb-screw, 26, the head of said bolt being beveled on one side, so as to bear upon the edge of the cutter, as represented in Fig. 12. Thus the cutter can be adjusted, taken out, or inserted, at pleasure. The polisher P' is also confined in the stock by means of a dovetail, in the same manner as the cutter. No screw, however, is required, as it can be driven in sufficiently tight. Thus it is obvious that polishers of any required length or shape (straight, concave, or convex) may be used at pleasure to finish heels of any size or fashion.

The utility of combining the cutter and polisher in a single stock is also obvious, for the handle can first be turned on pivot 25, so as to bring the cutter P into the right position to pare the heel, and when that operation has been performed the handle can be instantly turned so as to bring the polisher P' into the proper position to polish the heel, and thus no time will be lost in changing and adjusting the tools.

27 (see Fig. 6) is a pin against which the tool-stock 24 may rest to steady the cutter in paring, or the pivot 25 may be screwed down so fast as to hold the tool in place. For polishing, however, the hand of the operator is only required to guide and steady the tool.

The "lifts" of leather composing the heel

are first cut out by a die, so as to require as little paring as possible. The nail-holes and also a central hole are punched at the same operation. The lifts are then moistened, pasted, or cemented, and placed together in the proper position, and the nails inserted in the holes. The shoe is then put over the heel-bed T, as represented in Fig. 1, there being distance enough between the top of L and shaft F for the largest-sized shoe to vibrate without touching L with its toe. Wheel 17 is now turned so as to force the nails through the lifts and sole and clinch the points against the face of T. Being thus held between R and T, the heel is ready to be pared. The cutter 14 being now swung into the right position, the machine is set in motion, and (as it is evident from the foregoing description) the heel of the shoe will be vibrated, so as to present the whole of its curvilinear edge to the cutter, which will be so moved and guided as to give the shape required. Cutter 14 is now swung back and polisher P' brought forward so as to bear upon the heel, by means of which, as the shoe is vibrated, the heel will be polished.

The application of the cutter and polisher combined, Figs. 11 and 12, and also of cutter P, Fig. 9, has been described above.

Thus the operations of attaching, paring, and polishing shoe-heels can be performed with great rapidity, and the heels produced will be uniform and of the most desirable shape and perfect finish.

What I claim as my invention, and desire to secure by Letters Patent, is—

1. The cams V' and 16, in combination with the slides I, J, K, and L, and the tool-stock 24, constructed and operated as and for the purposes described.
2. The combination of the adjustable crank C, the arm D, and the chains E E' with the rotating pattern-block G, constructed and operated substantially as described.
3. The tool-stock 24, constructed as described, in combination with the arms N and M, substantially as above set forth.

JACOB JENKINS.
